UNITED STATES PATENT OFFICE.

WALTER A. CHANDLER, OF LOWELL, ASSIGNOR TO GEORGE DRAPER & SONS,
OF HOPEDALE, MASSACHUSETTS.

SPINDLE.

SPECIFICATION forming part of Letters Patent No. 498,952, dated June 6, 1893.

Application filed December 17, 1891. Serial No. 415,327. (No model.)

To all whom it may concern:

Be it known that I, WALTER A. CHANDLER, of the city of Lowell, in the county of Middlesex, in the State of Massachusetts, have invented a certain new and useful Improvement 5 in Spindles; and I declare the following to be a specification thereof, reference being had to the accompanying drawings.

Like letters indicate like parts.

Figure 1 is a view of my invention, partly in side elevation and partly in central, vertical section, the spindle being shown supported by the bolster and on the adjustable step. Fig. 2 is a side elevation of my improved bolster 15 in engagement with the adjustable step. Fig. 3 is a view of the bolster casing in central, vertical section, with the bolster and step in side elevation, within said casing, but not in engagement with each other. Fig. 4 is 20 a cross section on line 4, 4, of Fig. 1. Fig. 5 is a cross section on line xx of Fig. 1. Fig. 6 is an elevation of the spring pin.

My invention relates to the general class of spindles and more especially to the bolsters 25 and steps thereof.

It consists of the combination with a spindle, of an adjustable step, having a square head and a screw-threaded stem, the latter being engageable with a central screw-threaded 30 bore at the bottom of the oil chamber, within the casing; a bolster, having a tapering bore and a shoulder which rests upon a shoulder within the casing and provided with a locking portion, hexagonal in cross section, with 35 plane faces to lie in contact with similarly disposed plane faces in the bore of the casing, and also having at its lower end a square opening, adapted to receive the head of the adjustable step, as hereinafter particularly 40 specified.

In the drawings A represents the spindle, of tapering form. The foot of the spindle is shown at a and the whirl at b . The casing B has the central, tubular bore c , extending 45 far enough to receive the bolster, which bore terminates with the oil chamber d . The oil chamber d is tubular, but has a less diameter than the bore c , so as to leave a shoulder e . At the bottom of the oil chamber d , is a small, 50 central bore f extending down into the solid

portion of the casing B and provided with a screw-thread.

D is the oil cup with ducts g leading therefrom to the bore c of the casing B.

C is a spring pin having a screw-threaded 55 end, by which it is secured to the bolster casing. The pin is made of tempered metal and is flattened, so as to easily bend, and at its upper end has a bent end z , bent angularly, as shown. The pin C serves to prevent the 60 rise of the spindle from the bolster by extending its head over the whirl.

The bolster E is cylindrical upon its outer surface to fit the bore c of the casing B, and tubular to receive the spindle A. The bore 65 of the bolster is tapered, as shown in Fig. 1, to adapt it to the taper of the spindle. The bolster has the oil ducts h and its exterior surface is cut away sufficiently to receive the fibrous or woven sleeve F, which is to be saturated with oil. Near its bottom, the bolster is provided with a circumferential shoulder m and also with a locking portion, integral 70 therewith, shown at n , with plane exterior faces, hexagonally disposed, and terminates 75 with a cylindrical portion o . The bore of the bolster at its lower part is made square in cross section, as seen in Fig. 4.

The step has a square head p and a cylindrical screw-threaded stem or shank q , which 80 engages the bore f of the casing B.

The spindle A is supported by its tapering sides resting against the tapering bore of the bolster and also by the foot a , resting on the top of the head p of the step. By its continuous and rapid revolution, it becomes worn, and some device is necessary in order to adjust it to compensate for such wear. This I accomplish by making the step, upon which 85 its foot rests, adjustable in a vertical direction. This step by means of its screw-threaded stem q , which enters the screw-threaded bore f of the casing B, is capable of a vertical adjustment to the required degree, when turned upon the screw threads. This turning 90 of the step is effected by the rotation of the bolster by hand. As the lower portion of the bore of the bolster is made square in cross section, it serves as a key and receives the square head p of the step and turns the step, 95 100

while at the same time it is to some extent movable longitudinally on the head *p*.

The portion of the bore *c* of the casing *B*, commencing at the shoulder *e* and extending 5 downward to a distance equal to the length of the portion *n* of the bolster *E*, has plane sides, hexagonally disposed, which, when in contact with the surfaces of the portion *n*, form locking faces, as seen in cross section in 10 Fig. 5. To adjust the bolster, it should be lifted by hand sufficiently to bring the locking faces *n* up out of the hexagonal portion *s* of the bore *c* of the casing, into the tubular portion of said bore. It is now free to rotate, 15 but as it has not been lifted off the head *p* of the step, said step rotates with it. It is turned as far as necessary for the desired adjustment and thereby raises or lowers (as the case may be), the step, by the engagement of the 20 screw threads of the parts *q f*, and, when correctly adjusted, the bolster is pressed down again by hand and the plane faces again are locked, but in a new position, while the head *p* of the step is received deeper or lower down, 25 or farther up (as the case may be), in the bore of the bolster, as required for the adjustment. If the step is screwed lower down into the casing, the spindle descends farther into the bore of the bolster and fits more 30 snugly; while, if the step is unscrewed, it rises and the spindle is looser in the bolster.

I have specified and shown the faces of the part *n* of the bolster and the corresponding recess *s* in the bore *c* as hexagonal. They 35 may, however, be square, octagonal, or have any number of angularly disposed vertical faces. I prefer, however, the six faces shown, and by means of these, I can vertically adjust the step to an extent equal to one sixth of 40 the distance determined by the pitch of the threads; that is, by lifting the bolster out of its locking position and turning it one sixth of a revolution, I can again lock it in place, but by this movement I have also altered the 45 height of the step by one sixth of a revolution of the screw shank *q*, but without disengaging the head *p* of the step from the bolster or key.

The construction shown furnishes a supe-

rior locking mechanism which is easily operated; gives an independent support to the bolster, as well as to the step, and admits of a finer vertical adjustment than has heretofore been practicable. The oil chamber is of greater capacity than usual, and is free from 55 all liability of leakage, as it is not tapped from the outside for any rivets or locking pins, as in some of the well-known devices. The step is cheaply made from bar metal, with the shank turned for a screw, while the bolster and case have only central bores and apertures. As the bolster rests upon its shoulder and projects therefrom below, it yields to the vibration of the spindle in every direction without hinderance. 65

I claim as a novel and useful invention and desire to secure by Letters Patent—

1. In combination with a bolster casing, having a screw-threaded bore, a rotatable step, having a head with angularly disposed plane 70 faces and a screw-threaded stem to engage with said bore, and a rotatable bolster mounted in said casing and having an opening at its lower end adapted to receive the head of the step and to turn the step, substantially as 75 and for the purpose specified.

2. The combination of the bolster casing *B*, having the bore *c*, the screw-threaded bore *f* and the recess *s* with angularly disposed plane sides, the rotatable step, having the 80 head *p* with angularly disposed plane faces and the screw-threaded stem *q*, the rotatable bolster *E* mounted in the bore *c* of the casing *B* and having an opening at its lower end adapted to receive the head *p* and to turn the 85 step, and also having the locking portion *n* with corresponding angularly disposed plane faces to enter said recess *s*, substantially as and for the purpose specified.

3. In combination with a spindle and bolster-case, an adjustable step provided with a head and a bolster having at its lower end a device adapted to engage said head, substantially as and for the purpose specified. 90
